UNITED STATES PATENT OFFICE

163,177

DRESS

Helen Alice Georgiades, Brooklyn, N. Y., assignor to Prim Fashions, Inc., New York, N. Y.

Application December 14, 1950, Serial No. 13,437

Term of patent 7 years

(Cl. D3—26)

To all whom it may concern:

Be it known that I, Helen Alice Georgiades, a citizen of the United States of America, residing in Brooklyn, county of Kings, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

Fig. 3 is an enlarged fragmentary view of the dress shown in Fig. 1, illustrating one of the appliqued flowers in detail.

I claim:

The ornamental design for a dress, substantially as shown and described.

HELEN ALICE GEORGIADES.
